UNITED STATES PATENT OFFICE.

LIBANUS M. TODD, OF ROCHESTER, NEW YORK, ASSIGNOR TO TODD PROTECTOGRAPH COMPANY, OF ROCHESTER, NEW YORK, A CORPORATION OF NEW YORK.

DESIGN FOR A CASING FOR PRINTING APPARATUS.

51,004.

Specification for Design.

Patented July 3, 1917.

Application filed April 26, 1917. Serial No. 164,808. Term of patent 14 years.

To all whom it may concern:

Be it known that I, LIBANUS M. TODD, a citizen of the United States, residing at Rochester, in the county of Monroe and State of New York, have invented a new, original, and ornamental Design for Casings for Printing Apparatus, of which the following is a specification, reference being had to the accompanying drawing, forming part thereof, in which—

Figure 1 is a top plan view of the casing, showing my new design, and,

Fig. 2 is a perspective view of the same.

I claim:

The ornamental design for a casing for printing apparatus, as shown.

LIBANUS M. TODD.

Witnesses:

EDNA K. BOOTH,
E. H. CUMPSTON, Jr.
